UNITED STATES PATENT OFFICE

PETER LAZZARI, OF PITTSBURGH, PENNSYLVANIA

TOY PERFORMER

Application filed April 24, 1928. Serial No. 272,510.

The present invention relates to a new and improved toy. In particular the invention has for its object the production of a toy juggler which simulates more accurately than heretofore the action of a juggler of a ball or other object.

Heretofore toys of this nature in which a figure of a person throws a ball or other object from hand to hand were not truly representative of the action which takes place and therefore not completely satisfying to the mind of the child user, nor to the esthetic sense of the child user or buyer. As a result toys of this nature have not been in extensive use. The devices of the prior art have the defect of not causing the action to take place in a natural and expected way, because of the fact that the ball or other object moved from one hand to another of the juggler or figure in a plane which is not the plane in which one would normally expect the ball or other object to move. In the devices of the prior art, the ball or other object moves in a plane containing the head or body of the figure and hence the ball or object usually passes in its motion from one hand to another directly above the head of the figure. Such operation, as will be readily observed, results in the unnatural action referred to above.

The device of the present invention causes the ball or other object of the juggler or object manipulator to pass from hand to hand in a plane more or less in front of the head and face of the figure represented, thereby simulating the action of a juggler in a highly pleasing and attractive manner and possessing the advantages enumerated.

A further advantage of the present invention is that the support for the ball or other object which is moved from one hand of the figure to the other is supported by a rod decorated more or less in a manner similar to the body of the figure so that as the rod moves across the figure in carrying the ball the rod will tend to disappear, producing therefore a more perfect illusion.

Figure 1 of the drawings accompanying this application, and forming part thereof, shows a front view of the toy; Figure 2

shows a cross section through the base of the toy on the line II—II of Figure 1 looking in the direction of the arrows and illustrates a form of driving mechanism which may be used; Figure 3 shows a detail of part of the driving mechanism viewed along the line III—III of Figure 2 and looking in the direction of the arrows.

The numeral 1 represents any figure such as a clown or other performer. The arms 2, 2 of the performer or figure are outstretched and the elbows so bent that the palms of the hands 3, 3 extend considerably in front of the plane of the face of the figure. By this arrangement the ball or other object 4 may move from hand to hand in a plane in front of the face of the performer 1.

The ball 4 is supported by means of a rod 5, pivoted on a rod 6. The rod 5 is provided with an enlarged portion 7 at its lower end and this enlarged portion is provided with a slot 8.

Suitable spring driving means indicated generally by the numeral 9 may be of any approved and known construction. This driving means comprises intermeshing gear wheels 10 and 11. The gear 11 is fixed on the shaft 12 which also carries the governor 13. Also fixed to the shaft 12 and rotating therewith is a disc 14 provided with a pin 15. As the disc 14 is rotated under the influence of the driving mechanism, the pin 15 moves back and forth in the slot 8 in the enlarged portion 7 of the rod 5. This causes the rod 5 to swing as a pendulum about its pivotal support 6. The ball or other body 4 attached to the end of the rod 5 moves in an arc between the hands 3, 3. The arms 2, 2 and the pivotal support 6 must be so positioned that the amplitude of the motion of the ball represents a complete arc extending from one hand to the other.

The rod 5 is colored with spots corresponding more or less with the spots on the body of the clown, so that the motion and presence of the rod appears to disappear from perception, especially when the ball 4 is of a bright and distinctive color affording a sharp contrast.

Having described my invention what I claim is:

A toy comprising in combination the representation of a figure of an animal having two stationary outstretched arms extending before it, a rod pivoted at a distance below said outstretched arms and near the base of said figure and adapted to oscillate before said figure and at one end of its path of oscillation approaching the end of one of said outstretched arms and at the other end of its path of oscillation approaching the end of the other of said outstretched arms, a body attached to said rod and so positioned on it that oscillation of the rod about its pivot causes said body to move from the position of one outstretched arm to the other, and means carried by said toy operable to store energy for oscillating said rod and means for bringing about the oscillation of said rod by said stored energy.

In testimony whereof I affix my signature.
PETER LAZZARI.
